Henry Williams

UNITED STATES PATENT OFFICE.

GEORGE M. FISKE, OF NEWTON, MASSACHUSETTS.

BRICK-WORK CONSTRUCTION.

SPECIFICATION forming part of Letters Patent No. 415,772, dated November 26, 1889.

Application filed September 11, 1889. Serial No. 323,656. (No model.)

To all whom it may concern:

Be it known that I, GEORGE M. FISKE, of Newton, in the county of Middlesex and State of Massachusetts, have invented a new and useful Improvement in Brick-Work Construction, of which the following is a specification.

This invention relates to the construction of brick-work for building-fronts, &c., such construction consisting in the promiscuous use of various sizes and proportions of rectangular bricks in such a manner as to produce the effect or character of broken or irregular ashler in brick-work.

The drawing shows a front elevation of a portion of a building-front of brick-work, illustrating my invention.

It will be seen that the bricks are of different sizes, but are all rectangular, some, as A B, being equilateral, and some, as C D, being otherwise. They are put together or laid

promiscuously, so as to present the appearance in brick-work of what would be broken or irregular ashler in stone-work, and a building-front constructed in brick-work of this character presents a fine appearance. 25

Having thus fully described my invention, what I claim, and desire to secure by Letters Patent, is—

In the construction of brick-work, a collection of different-sized bricks of the shape of 30 equilateral and non-equilateral rectangles used or laid together promiscuously, whereby the effect or appearance in brick-work is produced of irregular or broken ashler, substantially as described.

GEORGE M. FISKE.
